UNITED STATES PATENT OFFICE.

WILLIAM A. SPEEGLE, OF MORGANTON, NORTH CAROLINA, ASSIGNOR OF ONE-EIGHTH
TO WALTER E. WILSON, OF MORGANTOWN, NORTH CAROLINA.

COMBINED DRILL AND GRINDING MACHINE.

Application filed June 6, 1922. Serial No. 566,255.

To all whom it may concern:

Be it known that I, WILLIAM A. SPEEGLE, a citizen of the United States, residing at Morganton, in the county of Burke and 5 State of North Carolina, have invented new and useful Improvements in Combined Drill and Grinding Machines, of which the following is a specification.

This invention relates to a combination 10 drilling and grinding machine, the general object of the invention being to provide a support in which is vertically movable a table which carries a motor and its shafting and gears and which has a depending arm 15 in which is supported the driven shaft which is to receive the tools and which is driven from the motor.

Another object of the invention is to provide means whereby the table can be adjusted in the support either by the motor or by hand.

Another object of the invention is to provide means for rotating the tool and at the same time causing the tool to travel about 25 a circular path, thus making the device capable of operating on the interiors of cylindrical members.

The invention also consists in certain other features of construction and in the 30 combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:—

40 Figure 1 is an elevation of the invention with parts broken away.

Figure 2 is a front view thereof.

Figure 3 is a section on line 3—3 of Figure 1.

45 Figure 4 is an enlarged detail view of the reversing mechanism for the feed screw.

Figure 5 is a longitudinal sectional view through the tool carrying arm and its associated parts.

50 Figure 6 is a section on line 6—6 of Figure 1.

Figure 7 is a bottom plan view of the bearing block and its supporting frame.

55 Figure 8 is a section on line 8—8 of Figure 1.

In these views 1 indicates a base having a rear raised extension 1^a on which the member 2 is slidably supported and 3 indicates a hollow upright which is slidably mounted on the member 2 and connected therewith by a dove-tailed joint as shown at 3^a. Thus the upright may be adjusted in two directions at right angles to each other. The upright is provided with guideways for the platform 4 which is vertically movable in the upright. This platform carries the motor 5 and the shafts and gearing hereinafter referred to. A depending arm 6 is connected with the front end of the platform and a hollow shaft 7 is journaled in this arm. The upper end of this shaft has secured thereto a worm gear 8 and the lower end thereof has secured thereto a frame 9 in which is slidably mounted a block 10. A spring 11 tends to hold the block at one end of the frame and the block is adjusted in the frame against the spring by means of the set bolt 12. An arbor 13 is eccentrically mounted in the block, this arbor carrying an emery wheel 14 or another tool. A vertical shaft 15 extends into the hollow shaft 7 and the lower end of this shaft is connected by a small shaft 16 with the arbor 13, this shaft 16 being provided with universal joints 17. A beveled gear 18 is connected with the shaft 15 and a pulley 19 is also connected with said shaft. The motor shaft 20 has slidably mounted on its outer end a beveled gear 21 which is adapted to engage with the gear 18. This gear 21 is adapted to be moved into and out of engagement with the gear 18 by means of the handle 22. A pulley 23 is secured to the motor shaft 20 and a belt 24 passes over the pulleys 23 and 19. Suitable guiding pulleys 25 are also provided for the belt. It will thus be seen that the tool carrying arbor can be rotated through means of the bevel gears or by means of the belt and pulleys. When the parts are to be driven from the belt the bevel gears are disengaged, as will be understood. The motor shaft 20 also carries a pinion 26 which meshes with a pinion 27 on a shaft 28 which is journaled on the platform and this shaft 28 carries a worm 29 at its outer end which engages the worm gear 8 so as to rotate the hollow shaft 7. The shaft 28 also carries a worm 30 which engages a worm gear 31 which is carried by a vertical stub shaft 32 which is mounted on the plat- 110

form. This shaft also carries a pinion 33 which may engage a pinion 34 which is secured to the screw shaft 35 which is journaled in the upright and is so connected with the platform that when the shaft is moved longitudinally by its engagement with the nut 36 the platform will also be moved vertically in the upright. Instead of having the gear 33 mesh directly with the gear 34 I may so adjust the worm gear 31 and the worm 30 as to space the gears 33 and 34 apart to permit a reversing mechanism to be used to cause the platform to be moved up and down in the upright. Such reversing means consists of a member 37 which is pivoted on the shaft 32 and which carries a pair of intermeshing gears 38. The member also carries a pair of arms 39 and a spring carrying pin 40 which is adapted to be connected with a part of the platform. The parts are so arranged that in one position of the member one gear 38 will be engaging the gear 33 and the other gear 38 will be engaging the gear 34 so that the gear 34 will be rotating in the same direction as the gear 33. In another position of the parts, however, the small gear 38 will be out of engagement with both the gears 33 and 34 and only the large gear 38 will be meshing with said gears. Then the gears 33 and 34 will be rotating in opposite directions. The spring and pin 40 will hold the member in either one of its two positions after the member has been moved to this position. The member is moved by the adjustable stops 41 on the upright which are provided with the springs 42 which are engaged by the arms 39. These springs 42 help the spring on pin 40 to complete the movement of the member 37 after it is moved to a certain extent by the engagement of the arms 39 with the inclined parts of the stops 41. By this means the platform will be moved downwardly by the gears and shafts connecting the motor with the feed screw until one of the arms 39 strikes the lower stop 41 when the reversing device or member 37 will be swung into its other position so as to reverse the movement of the feed screw and then the platform will be moved upwardly until the other stop is engaged by the arm 39 when the parts will be again reversed and the platform fed downwardly. Thus the platform is reciprocated vertically and by adjusting the stops the extent of this movement can be varied. The rotation of hollow shaft 7 will move the tool 14 in a circular path at the same time that the tool is revolving around its axis by the rotation of the arbor 13 through the means specified. Thus when the device is used to grind the interior of a cylinder, for instance, the tool will be brought into engagement with all parts of the cylinder wall as the tool is revolving for the tool will not only

be rotating in a circular path but it will also be moving up and down.

I make the nut 36 in two parts, as shown at 36', so that said parts can be separated by the handles 36'' to disengage the nut from the shaft to permit the platform to remain stationary. Each part of the nut is pivoted to a support 36* which is connected with the upright.

The platform is counter balanced by the weights 43 which are connected with the platform by the cables 44, said cables passing over pulleys 45.

I may also provide manually operated means for raising the platform, such means consisting of a rack 46 placed on the upright, which is engaged by a toothed wheel 47 placed on a shaft 48 carried by the platform and which is rotated by a handle 49.

I also provide a work supporting table 50 which is rotatably mounted on an arm 51, detachably connected with a support 52 which is vertically adjustable on the upright by means of the rack 53 and the toothed wheel 54 which is carried by a shaft 55 90 which is journaled in the support and which is provided with a handle 56.

By having the arbor connected with the motor shaft by the bevel gears and the belt and pulleys, the said arbor and the tool carried thereby can be driven at different speeds without changing the speed of the motor. Thus when the device is to be used for grinding and an emery wheel is placed on the arbor the parts should be driven at great speed and thus the belt and pulleys are made use of, the bevel gears being disengaged. When the device is to be used for drilling purposes and a drill is attached to the arbor then the parts should be driven at slow speed so that the bevel gears are placed in engagement with each other and the belt slackened or taken off. By making the block 10 adjustable the diameter of the circular path in which the tool is revolved can be adjusted.

It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:

1. A device of the class described comprising an upright, a platform movable therein, a feed screw connected with the platform, a nut carried by the upright engaging the screw, a motor on the platform, a tool carrying member actuated by the motor, means actuated by the motor for rotating the feed screw, reversing means associated with such means for turning the feed screw in either direction and adjustable stop means for 130

automatically actuating the reversing means to cause the platform to be reciprocated in the upright.

2. A device of the class described comprising an upright, a platform movable therein, a motor carried by the platform, a tool carrying member, means actuated by the motor for moving the same in a circular path while it is being rotated, a feed screw carried by the platform, a sectional nut

carried by the upright for engaging the feed screw, means for moving the sections apart to free them from the screw, means for driving the feed screw from the motor, reversing means for the screw and adjustable and automatic means for actuating the reversing means to cause the same to reciprocate the platform. 15

In testimony whereof I affix my signature.

WILLIAM A. SPEEGLE.
